CLAIM

The ornamental design for a lampshade, as shown and described.

DESCRIPTION

FIG. 1 is a first perspective view of a Lampshade showing our new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion A in FIG. 1.

The evenly broken lines in the drawings illustrate portions of the article that form no part of the claim.
